UNITED STATES PATENT OFFICE.

ERNEST FRANKLIN HODGSON, OF DOVER, MASSACHUSETTS.

CHICKEN-BROODER.

SPECIFICATION forming part of Letters Patent No. 644,599, dated March 6, 1900.

Application filed November 2, 1899. Serial No. 735,612. (No model.)

To all whom it may concern:

Be it known that I, ERNEST FRANKLIN HODGSON, a citizen of the United States, residing at Dover, State of Massachusetts, have 5 invented certain new and useful Improvements in Chicken-Brooders, of which the following is a specification.

My invention relates to a chicken-brooder; and its object is to prevent undue heating of 10 the parts of the burner, while at the same time utilizing the heat, so as to render it unnecessary to waste the heat in order to properly ventilate and cool the parts of the burner or heater. In brooders as now constructed, 15 in which lamp-stoves are used as the heating means, the heat is communicated from the wick-tube and chimney to the oil tank or reservoir, which becomes hot, with its contents, and this causes an overheating of the brooder, 20 which requires so much ventilation as to be wasteful of the heat and to make it difficult to maintain an even temperature. I aim to obviate this difficulty by my invention, and I do it in a very simple manner—namely, by 25 the interposition of a diaphragm between the upper end of the wick-tube and the oil-tank and by exposing the oil-tank on all sides to the atmosphere, so that it is kept cool and prevented from overheating.

30 In the accompanying drawings I have illustrated my invention, showing, in Figure 1, a sectional view with the oil-tank and chimney in side elevation. Fig. 2 is a perspective view of the invention. Fig. 3 shows a front view 35 of a brooder with my attachment in place.

In carrying out my invention I use a plate 40 of sheet metal A, having a turned-up front end B, forming the front wall of the lamp-chamber. Above and resting upon this plate is the chimney C of a lamp-stove, while beneath the position of the plate A is an oil-tank D, having a wick-tube which extends 45 up through an opening in the plate A directly beneath the chimney. Thus the plate A serves as an interposed diaphragm between the oil-tank and the flame and protects and shields it from the heat, the oil-tank occupying the space beneath the plate A, which is open to the front and exposed to the outside air, and 50 this also tends to keep it cool, as the air passing from the front to the openings in rear of the lamp-body is caused to flow over and around the said lamp-body, whence it flows

up through the openings and in an opposite direction above the plate, escaping by openings in the upturned end B. The oil-tank has a filling-tube b extending to the front, so that it may be filled easily. The wick-raising spindle is also extended to the front, as shown at c. The plate A fits in guides in 55 the sides of the brooder-opening, as shown at d, and the whole attachment may be drawn out whenever required.

It is not always necessary to use a chimney, and, as shown in Fig. 2, in such cases the end 60 of the burner projects above the diaphragm, so as to supply the heat to the lamp-chamber, while the oil-tank is beneath the diaphragm surrounded by the outside air.

What I claim is—

1. In a chicken-brooder, the combination with the body portion having a brooding-chamber, and an open space centrally beneath the same, of a plate located in said space and forming an elongated heating-chamber said 70 plate having an upwardly-extending front, and a lamp-body carried below said plate and having a burner above said plate, and openings in the rear of said lamp-body and in said upwardly-extending front whereby a draft of 75 air is caused in one direction beneath said plate and in the opposite direction above, substantially as described.

2. In a chicken-brooder, the combination with the body portion having a brooding-chamber and having a centrally-open space, of a plate slidably located in said space and having an upwardly-turned front provided with perforations, a lamp-body located below 85 said plate and having a burner located above 90 the same, and openings in said plate in rear of said lamp, substantially as described.

3. In combination with the plate A, a chimney secured thereto, an oil-tank beneath the same and an elongated filling-tube extending 95 from the oil-tank to the front and an elongated wick-raiser stem extending from the wick-tube to the front, substantially as described.

In testimony whereof I affix my signature 100 in presence of two witnesses.

ERNEST FRANKLIN HODGSON.
